UNITED STATES PATENT OFFICE.

PAUL A. HOUGHTALING, OF RIVERTON, NEW JERSEY, ASSIGNOR TO THE CURTAIN SUPPLY COMPANY, OF NEWARK, NEW JERSEY, A CORPORATION OF NEW JERSEY.

CURTAIN-FIXTURE.

No. 856,874.

Specification of Letters Patent.

Patented June 11, 1907.

Application filed February 23, 1905. Serial No. 247,006.

To all whom it may concern:

Be it known that I, PAUL A. HOUGHTALING, a citizen of the United States, residing at Riverton, New Jersey, have invented certain new and useful Improvements in Curtain-Fixtures, of which the following is a specification.

My invention relates to a curtain fixture for holding spring-actuated shades or curtains against the pull of the shade roller spring, and more particularly to that class of curtain fixtures wherein the curtain is provided at its lower end with a hollow tube commonly called a shade stick, and the latter is provided at its ends with heads carrying friction tips which are forced into holding contact with the bottom of a groove in the window frame by outwardly forcing springs.

The object of my invention is to provide an inexpensive yet efficient and practicable fixture of the class above mentioned.

To this end my improvement consists essentially in the combination with a curtain stick and its guiding head of a friction tip or pad elastically connected with the head and attached to a sliding rod or other retracting means carried by the stick.

In the drawings—Figure 1 represents the lower end of a shade or curtain carrying a fixture and shown in relation to the grooves of the window frame, a fragmentary portion of the latter being shown partly in section; Fig. 2 is an enlarged sectional elevation showing one form in which my invention may be embodied; Fig. 3 is a plan view of a blank for forming the elastic plate for carrying the friction pad.

In the drawings A represents the curtain in the lower margin of which is carried a tubular curtain stick B. Within this stick are the longitudinally slideable rods C carrying at their outer ends guiding heads and friction pads.

In the form of construction shown in Figs. 1, 2 and 3, the heads D are hollow metal boxes. Within the hollow of each of these heads is mounted an elastic plate or spring member E which may be made from a blank in the form shown in Fig. 3 and having its side portions e bent or folded along dotted lines so as to afford a seat for a friction pad e'.

The plate member E has an extension e² which may be secured at its outer end by a

screw d to the bottom wall of the head D. A second screw d' attaches the plate to the end of the sliding rod C and the latter is provided with a pinch handle e extending through and sliding in a slot in the curtain stick. The spring plate e will be so shaped that its body portion will be offset from the bottom of the head and its extension put under tension, thus tending to hold the pad e' in contact with the bottom of the groove with sufficient force to overcome the upward pull of the shade roller spring. The shade may be raised or lowered by pressing the pinch handles, thus withdrawing the friction pads from the holding contact, or the shade may be pushed up without pressing the handles. In order to vary the holding power of the pad, the tension of the extension e² may be regulated by a set screw d².

The pinch handles may, of course, be omitted and the fixture moved up and down without retracting the friction pads. By my invention I obviate the necessity of providing spring members within the shade stick itself and produce a fixture which will be cheap to construct and easily adjusted as to its holding power.

Other modifications may be made within the scope of the invention which comprises the general combination and organization of members recited in the claims.

I claim:

1. A curtain fixture comprising in combination a curtain stick, a guiding head carried by said stick, a friction pad, a spring member operating to force the pad into holding contact with the window frame, and means for varying the tension of the spring member.

2. A curtain fixture comprising in combination a curtain stick, a head carried thereby, a friction pad, a spring member operating to force the pad into holding contact with the window frame, a sliding rod connected with the pad support, and means for varying the tension of the spring.

3. A curtain fixture comprising a shade stick, a head carried thereby, a rod sliding in said head, a friction pad, a spring member operating to force the pad into holding contact with the window frame, the sliding rod being connected with the pad support, means for retracting said rod, and independent means for varying the tension of the spring.

4. A curtain fixture comprising a hollow curtain stick, a rod sliding therein, a hollow head at the end of the stick, and a spring member adjustably connected to the head and also connected to the rod, and having a friction pad mounted thereon and adapted to project beyond the face of the head and to be retracted within the hollow thereof, substantially as described.
5. In a curtain fixture, a head, a holding device having a spring part, and adjustable means for controlling the flexure of the spring, said means being carried by the head.
6. In a curtain fixture, a stick, a holding device operatively associated therewith, said holding device including a spring, and means adjustable independently of the stick to control said spring.
7. In a curtain fixture, a stick, a head, a holding device on said head, said holding device including a spring, and means adjustable to control said spring.
